UNITED STATES PATENT OFFICE

2,428,140

PUMP STROKE CHANGING MEANS

Garfield Brown, Minneapolis, Minn., assignor to
 The Northern Pump Company, Minneapolis,
 Minn., a corporation of Minnesota

Application October 27, 1943, Serial No. 507,828

4 Claims. (Cl. 74—60)

1

This invention relates to a pump of the swash plate type and particularly to a novel mechanism for changing the stroke of said pump.

Said type of pump comprises a tilting plate which is mounted for swinging movement about trunnions at opposite sides thereof. This plate forms or carries what is called a swash plate to which one end of the piston rods are secured. The plate is given an oscillating or gyrating motion to give movement to the piston rods and pistons and the amount of piston travel can be varied by swinging said plate about said trunnions.

In this type of pump high pressures are commonly used and in the rotation of the tilting and swash plate the pistons are at the intake side of the cylinder for part of a revolution and at the discharge side of the cylinder for the other part of the revolution. This reversal of pressure places great stresses upon the tilting plate and upon any mechanism which is provided for swinging it. Such a mechanism must be capable of easy and small movement and must be constructed to withstand the pounding which it necessarily takes in the operation of the pump.

It is an object of this invention therefore to provide a simple and efficient mechanism for varying the stroke of a swash plate type of pump.

It is a further object of the invention to provide a member preferably in the form of a fork secured to the tilting plate between the trunnions thereof, a pin secured in and extending between the arms of said fork and a member connected to said pin by movable connection and being movable about a longitudinal axis extending at right angles to the axis of the trunnions of the tilting plate, together with means for moving said member to swing said tilting plate.

It is more specifically an object of the invention to provide a tilting plate swingable about trunnions at opposite sides thereof, a fork secured to and projecting from said plate, a pin secured in and extending between the arms of said fork, a plunger movable longitudinally in a direction at right angles to the axis of said trunnions, said plunger having a member movable therein and carried by said pin and means for moving said plunger to swing said fork and said tilting plate.

It is still further an object of the invention to provide such a structure as above set forth together with a casing enclosing the tilting plate, having an opening through which said fork projects and a second casing secured to said casing and enclosing said fork and a portion of said plunger so that oil or fluid from said first mentioned casing can pass into said second casing.

These and other objects and advantages of the invention will be fully set forth in the following description made in connection with the accompanying drawings in which like reference char-

2

acters refer to similar parts throughout the several views and in which:

Fig. 1 is a view in horizontal section taken on line 1—1 of Fig. 2 as indicated by the arrows;

Fig. 2 is a vertical section taken on line 2—2 of Fig. 1 as indicated by the arrows;

Fig. 3 is a partial view in side elevation of a plunger used;

Fig. 4 is a vertical section taken on line 4—4 of Fig. 5 and

Fig. 5 is a view in side elevation.

Referring to the drawings a portion of a pump of the swash plate type is shown comprising the tilting plate 10 which is swingable about the axis of trunnions 10a. A pump of the type referred to is shown in the patent to John B. Hawley, Jr., et al. #2,307,041, granted January 5, 1943. Plate 10 has a boss 10b at one side between the trunnions thereof and a member 11 is secured to boss 10b by the headed bolts 12. Member 11 is in the form of a fork and has projecting parallel arms 11a. A pin 13 is secured in and extends between arms 11a, said pin being secured in any suitable manner as by one or more screws 14. The other

end of pin 13 is flanged to hold it from endwise movement and is tapped to facilitate assembly and disassembly. Member 16 embraces pin 13 being journaled thereon and in the embodiment of the invention illustrated member 16 is pro-

vided with a cylindrical periphery as shown in Fig. 4. Member 16 is also fitted for sliding movement in a bore 18a in an enlarged portion 18b of a shaft or plunger 18. Portion 18b is provided with elongated openings 18c at opposite sides which extend from its exterior into bore 18a. Pin 13 passes through the openings 18c and thus passes through member 16 which is disposed between arms 11a. Portion 18b is provided with flat sides 18d which extend parallel to the inner sides of arms 11a, it being noted that there is some clearance between sides 18d and the inner sides or arms 11a. Plunger 18 extends some distance at either side of portion 18b and is of cylindrical form fitting in bores in casings 20 and 21. Casings 20 and 21 have chambers therein to which liquid may be supplied through openings 22a in cap members 23 secured to casings 20 and 21 respectively by bolts 24. A pipe 25 is connected

to one member 23 and a pipe 26 is connected to the other member 23. Members 23 engage suitable gaskets 27 in casings 20 and 21 to insure a tight seal. Pipes 25 and 26 will be connected to some suitable source of fluid under pressure so

that fluid can be applied to one end of member 18 and to one of the casings 20 and 21 and be exhausted from the other of said casings. Member 18 thus forms a plunger and is arranged to be moved by fluid supplied through pipes 25 and 26.

As shown in Fig. 4 the ends of member 18 are pro-

vided with bores 18e. The casings 20 and 21 are provided with cylindrical flanges 20a and 21a respectively, which are secured to the ends of the casing 30 by circumferentially spaced bolts 31. A suitable gasket 32 is disposed between said flanges and casing 30 to insure a liquid-tight fit and lock washers 33 are shown as disposed beneath the heads of bolts 31. Casing 30 is also provided with a base flange 30a and this is secured by spaced headed screws 35 to the pump casing 36 which encloses tilting plate 10 and the pump pistons and other parts. Casing 36 is provided with an opening 36a through which boss 10b and fork 11 extend. Lock washers 37 are shown as disposed beneath the heads of bolts 35, which heads are countersunk in flange 30a. Casing 30 has bosses 30b at opposite sides provided with bores 30c which are axially aligned with pin 13. Pin 13 can thus be passed through one of the openings 30c for assembly or disassembly. Cover plates 39 are secured to the outer sides of bosses 30b over the bores or openings 30c by circumferentially spaced headed screws 40, having their heads countersunk into plates 39 and also having lock washers 41 beneath their heads.

Referring again to pin 13 it is pointed out that there is an appreciable clearance between said pin and member 18 where said pin passes through the latter. This clearance permits movement of member 18 about the axis of member 16.

The top of casing 30 is bored and tapped as shown at 30d to receive a plug (not shown).

In operation when it is desired to change the stroke of the pump by swinging plate 10 about its trunnions, fluid will be supplied through one of the pipes 25 or 26 and this will pass into the chamber of casing 20 or 21. This fluid will move plunger 18 longitudinally, moving member 16 and thus moving fork 11 and swinging plate 10. As fork 11 thus moves about the axis of the trunnions of plate 10 member or block 16 will move downward in member 18, pin 13 moving in openings 18c. The plunger 18 will be moved in one direction to increase the stroke of the pump and will be moved in the other direction to decrease the stroke. It will be held in the desired position by the presence of fluid in chambers 20 and 21. It will be noted that the mechanism provides movement about three axes. Relative movement of member 18 about the axis of pin 13 is provided. Relative movement of member 18 about the axis of pin 16 is possible and member 18 can turn to some extent about its own axis. This gives a complete universal motion between the operating member 18 and the plate 10 to be tilted. With this complete universal action of the connection or joint accurate alignment of the parts is not necessary, but at the same time any movement of member 18 is transmitted immediately to the tilting plate or box 10 with a minimum of lost motion. This is a great advantage in this structure of mechanism.

From the above description it will be seen that I have provided a simple and yet very efficient mechanism for adjusting the stroke of a pump. The connection between member 18 and fork 11 comprises nicely fitted parts with fairly large surfaces and these parts can move easily relatively to each other. As stated, the mechanism provides a complete universal motion. These pumps are usually used to pump oil and this oil can flow from the pump casing 36 through opening 36a into casing 30 so that the outer portion of the fork and members 16 and 18 will be thoroughly lubricated. The mechanism is very compact and

the tilting plate can be easily and accurately moved small distances and as stated, with a minimum of lost motion. The mass of the tilting plate is large and the mechanism for swinging it must be rugged and at the same time quite accurate. As above stated, the mechanism receives severe shocks in the operation of the pump and must be made very rugged to withstand such shocks. With the present construction the tilting plate can be easily moved in either direction as desired. The invention has been amply demonstrated in actual practice and found to be very successful and efficient.

It will of course, be understood that various changes may be made in the form, details, arrangement and proportions of the parts, without departing from the scope of applicant's invention, which generally stated, consists in a device capable of carrying out the objects above set forth, in the parts and combination of parts disclosed and defined in the appended claims.

What is claimed is:

1. A device for changing the stroke on a swash plate pump having a tilting plate swingable about trunnions at its opposite sides and a shaft with means for moving the same axially at right angles to the axis of said trunnions, having in combination, a fork secured to said plate at one side thereof and projecting substantially radially therefrom, a pin extending between and secured in the arms of said fork, a member journaled on said pin and having a periphery disposed about an axis at right angles to said pin, said shaft extending between the arms of said fork and having an opening therein in which said member fits and is movable at right angles to the axis of said pin.

2. The structure set forth in claim 1 said shaft having elongated openings therethrough through which said pin extends, said pin moving in said openings in the movement of said member.

3. A device for changing the stroke on a swash plate pump having a tilting plate swingable about trunnions at its opposite sides and a shaft with means for moving the same axially at right angles to the axis of said trunnions, having in combination, a member secured to said plate, projecting substantially radially at one side thereof and having spaced arms, a pin extending between and secured in said arms, the same extending parallel to the axis of said trunnions, and a member journaled on said pin and having a cylindrical periphery extending about an axis at right angles to said pin, said shaft having an opening therein in which said cylindrical periphery of said member fits and is movable at right angles to the axis of said pin, said pin extending transversely through said shaft.

4. A device for changing the stroke on a swash plate pump having a tilting plate about trunnions at its opposite sides and a shaft adjacent said plate with means for moving the same axially at right angles to the axis of said trunnions, having in combination, a fork secured to said plate and projecting radially from the periphery thereof substantially midway between said trunnions, a pin extending between and secured against rotation in the arms of said fork, said pin extending parallel to the axis of said trunnions, and a member journaled on said pin and having a cylindrical periphery extending about an axis at right angles to the axis of said pin and of much larger diameter than said pin, said shaft extending between said arms, said cylindrical periphery of said member fitting in an opening in said shaft, said mem-

ber being axially movable in said opening at right angles to the axis of said pin.
